ELECTRON TUBE

Ernst Brüche, Berlin-Reinickendorf (Ost), Germany, assignor to Allgemeine Elektricitäts Gesellschaft, Berlin, Germany, a corporation of Germany

Application September 24, 1932, Serial No. 634,705
In Germany September 25, 1931

3 Claims. (Cl. 250—27.5)

The present invention relates to electron ray tubes and principally to a cathode ray tube.

An important object of the present invention is to provide ways and means adapted to cause an electron-ray pencil to be deflected out of its direction into another direction without requiring the use of either electrical or magnetic fields. An arrangement of this kind offers particular advantages in connection with the construction 10 of electron-ray tubes whether these be employed for oscillographic, sound-film or television work, for instance, in connection with the photographic recording of an oscillographed action where the direct light produced by the electron ray in deviated position is unable to impinge upon the photographic plate or film.

A device of the said sort, according to the invention, is realizable by a metallic tubelet which has a width of 2 mm., for example, and the requisite curvature. The small diameter tubelet is kept at anode potential or at another suitable but different voltage. If the electron-ray pencil emanating from a hot cathode is caused to pass into the metallic tubelet as far as feasible coaxially 25 therewith, in the presence of slight volumes of gas, the pencil of electrons will be guided along the curvature of the tubelet and will leave the latter in the changed direction.

One special merit of this arrangement may be 30 regarded as residing in this fact that a magnetic field will not influence the electron-ray pencil inside the metallic tubelet. Moreover, a tubelet of the said sort may serve the purpose of causing the electron-ray pencil to proceed or flow in an exactly pre-determined direction, for example, 35 along the tubular axis of an oscillographic tube.

Practical arrangements could be made in such a way that the curved tubelet is placed inside the bulb of a Braun or cathode ray tube as shown by 40 Fig. 1, of the drawing while in other cases a modified form of arrangement as shown by Fig. 2, of the drawing may be used.

To refer now to the drawing, and first to Fig. 1, thereof, there is supported inside a curved vessel 1 a heated cathode 2. Opposite the cathode member 2 is disposed a curved metal tubelet 3 in such a way that, upon application of a suitable voltage to the tubelet by way of the lead 4, the electrons issuing from the cathode will be guided into 50 the opening 5 of the said tubelet. What issues then from opening 6 is a pencil of electrons travelling along the dotted line, and this electron pencil may be rendered visible in the usual manner by means of the fluorescent screen which is positioned in the path thereof. It will thus be seen

that the direction of the pencil at the outlet end of the tubelet 3 differs from the original sense of flow of the electron pencil at the place where it entered the tubelet. This pencil is influenceable by ways and means well known in the prior art 5 electrostatically, e. g., by the aid of deflector plates 8 or else may be controlled magnetically where desired.

The flared or enlarged inlet opening 5 of the metallic tubelet consists most conveniently of a 10 difficultly fusible metal such as molybdenum, while the rest of the tubelet may consist of some other metal such as copper which has its interior surface silver-coated, if desired. Instead of a metal tubelet an insulating tube which rendered 15 conductive in its interior surface could be employed. Such a structure might, for example, be an internally silver-coated glass tubelet.

In the embodiment here cited by way of example, the tubelet 3 serves and acts at the same 20 time as the anode element for the tube. In its stead, however, a distinct anode could be mounted between the heated cathode and the tubelet. The tubelet could then be kept at the same potential as the anode or else be maintained at a voltage differing therefrom according to whether or 25 not a change in velocity of the electrons is desired.

In order that any desired change in direction or deviation of the pencil of electrons may be 30 realizable, arrangements could be made also in the way shown by the modified arrangement in Fig. 2. In the modified form the cathode-ray tube consists of two vessels 10 and 11 which are connected by way of a flexible copper tube 9. 35 Contained within the vessel 10 is a hot cathode 12 which gives off electrons. This vessel is closed by means of a cap 13, e. g., of copper, into which the flexible copper tube 9 is fitted. Applying to tubelet 9, for instance, by way of lead 14, a suitable voltage of, say, a few hundred volts, the electrons will be deflected towards the opening 15 and they emerge from tubelet 9 at the opening 16 thereof and enter into the vessel 11 which most suitably is shut likewise by means of a copper cap 17. The electron pencils may then be rendered visible by the fluorescent screen 20.

The said copper tubelet 9 may be bent into any formation with the result that the electron-ray pencil is caused to flow in any desired direction. 50 It would thus be possible, for instance, to bend the pencil in such a direction that it will not be acted upon by whatever fields may prevail in space, say, by terrestrial magnetism.

This form of construction of the cathode-ray 55

5 tube moreover offers the advantage that deflector means such as deflecting coils 18 may be applied at any desired proximity to the pencil of electrons and at the same time at greater distance
10 from the place of generation of the pencil, while yet being located in the outside space. Another advantageous feature may be regarded to reside in that when the tube is connected with a pump, an appreciable pressure difference is maintainable between the two spaces; for instance, space or vessel 10 may be kept substantially free from gases, while inside space 11 slight volumes of gas may be present.

15 Inside tube 11, as well known in the earlier art, deflector plates 19 designed for insuring electrostatic deviation may be mounted.

Having now described the invention what is claimed is the following:

1. A cathode ray device comprising a pair of 20 independent envelope members each maintained at a different pressure, a source of cathode rays contained within one envelope, a fluorescent screen contained within the other envelope, a flexible tubular anode member connecting the 25 two envelopes and having an opening substantially adjacent the source of electrons in one envelope and an opening at the other end in the

second envelope extending substantially normal to the fluorescent screen, means for confining the electron beam passing within the tubular anode to a substantially central position coaxial therewith, and means for deflecting the electron stream issuing from the end of the tubular anode 5 adjacent the screen structure so as to cause the electron beam to traverse the fluorescent screen.

2. The cathode ray device claimed in claim 1 comprising in addition a metal cap member 10 provided for each independent envelope, said cap surrounding the flexible tubular anode member so as to seal the tubular anode within each ves-

sel.
3. A cathode ray device comprising a source of 15 electrons, a flexible tubular anode member to cause the electrons to be drawn from the source in the form of an electron pencil, a funnel-shaped mouth portion for said anode member, said mouth portion being constituted of a difficultly fusible material and constituting an inlet opening for said tubular anode and positioned substantially adjacent the source of electrons for receiving the emitted electrons, and a fluorescent viewing screen in the path of the electrons issuing 25 from the flexible tubular anode member.

ERNST BRÜCHE.
